UNITED STATES PATENT OFFICE

MELVIN E. VANSICKLE, OF NEWARK, NEW JERSEY, ASSIGNOR TO BRANDES LABORATORIES, INC., OF NEWARK, NEW JERSEY, A CORPORATION OF NEW JERSEY

ELECTRICAL PHONOGRAPH APPARATUS

Application filed March 17, 1927. Serial No. 176,088.

My invention relates broadly to electrical phonograph pick-up devices and more particularly to a compact construction and assembly of electrical phonograph pick-up.

5 One of the objects of my invention is to provide a construction of pick-up for electrical phonographs in which the parts of the pick-up may be readily assembled without the exercise of any large degree of skill for manufacturing a phonograph pick-up of a high degree of sensitivity inexpensively on a quantity basis.

Another object of my invention is to provide a phonograph pick-up construction of 15 the electrodynamic type wherein an armature member is positioned within a powerful permanent magnet field and associated with a field winding in such manner that movements of a stylus in accordance with a sound record 20 may impart vibration to the armature member for changing the condition of the electromagnetic winding for developing such differences in potential as will control the operation of an electron tube amplification system at large amplitude.

Still another object of my invention resides in the construction and arrangement of parts for an electrical phonograph pick-up as more fully described in the specification herein- 30 after following by reference to the accompanying drawings, in which:

Figure 1 is a side elevation of the phonograph pick-up device of my invention; Fig. 2 is a longitudinal cross-sectional view taken 35 through the phonograph pick-up device of my invention; Fig. 3 is a cross-sectional view taken through the phonograph pick-up on line 3—3 of Fig. 2; Fig. 4 is a lateral cross-sectional view taken on line 4—4 of Fig. 3; 40 and Figs. 5 and 6 are views of the armature member and stylus holder which I provide for the electrical phonograph pick-up device.

Referring to the drawings in more detail, 45 reference character 1 indicates a phonograph having a revolving record table 2 carrying a disc sound record 3. A swinging tone arm 4 is provided carrying the electrical phonograph pick-up 5 which fits by means of holder 6 into the end of the tone arm 4. The elec-

trical phonograph pick-up is supported from the holder 6 by the casing portion 7 which surrounds the parts of the phonograph pick-up. The entire assembly of parts of the phonograph pick-up is mounted from a permanent magnet 8 which is secured at its upper portion to the holder 6 by means of plate member 9 and securing screws 10. The permanent magnet 8 has a pair of parallel extending pole pieces 11 and 12 and between 55 these pole pieces, I provide pole members 14 and 15 in the form of yokes having opposite pole faces aligned with respect to each other as represented by 16 and 17 at one end and by 18 and 19 at the opposite end. The pole members 14 and 15 have up-standing lugs 20 and 21 connected thereto through which the securing bolt 23 passes. The securing bolt 23 serves as a spacing member for the pole members and may be adjusted in the 60 screw threaded lugs 20 and 21 and locked in position with respect thereto by sets of nuts 24 and a set of nuts 25. The pole members 14 and 15 are spaced from the pole pieces 11 and 12 by means of spacer blocks 26 and 27 65 through which the securing screws 28 and 29 pass. A ring shaped member 30 is provided for positively spacing the pole faces 18 and 19, the ring member 30 being secured to the pole faces by screw means 31. The pole 70 faces 18 and 19 are tapered toward each other for cooperating with laterally extending grooves 32 on opposite sides of the armature member 33. The armature member 33 is flat and extends through the electromagnetic 75 winding 34 which is mounted on the coil support 35. The upper end of the armature 33 is forked at 36 extending around opposite sides of the screw device 23. A flexible strip 37 apertured at 38 for the passage of the 80 screw device 23 extends from the upper portion of the permanent magnet 8 at 39 and is riveted to the armature 33 at 40. This strip 37 is flexible and permits the free vibration 85 of the armature 33 although the armature may, in this way, be held in a normally central position and excessive vibration damped. The armature 33 carries a stylus holder 41 on the end thereof for receiving a 90 stylus 42 which is secured in place by means 95 100

of a set screw 43. The entire assembly of parts for the phonograph pick-up is housed within a casing 44 secured by means of screw members 45 and spacer blocks 46 to the laterally extending member 9.

5 The electrical phonograph pick-up device of my invention has been found to be extremely efficient in operation and practical in construction.

10 While I have described my invention in one of its preferred embodiments, I desire it to be understood that modifications may be made and that no limitations upon my invention are intended other than are imposed by 15 the scope of the appended claims.

What I claim as new and desire to secure by Letters Patent of the United States is as follows:

1. An electrical phonograph pick-up comprising a supporting member, a permanent magnet carried by said supporting member, said permanent magnet having a pair of longitudinally extending parallel pole pieces, a pair of U-shaped pole members positioned 25 between said pole pieces, lugs integrally connected to said U-shaped pole members, means projecting through said lugs for aligning said pole members with the pole faces thereof directed toward each other, an electromagnetic winding positioned within said pole members, an armature member extending through said electromagnetic winding and pivotally mounted between said pole faces, means secured to the end of said armature 30 member for limiting the lateral movement of said armature member, a stylus carrier connected with the opposite end of said armature member whereby vibrations may be impressed upon said armature member from a 35 stylus positioned in said stylus holder.

40 2. An electrical phonograph pick-up comprising a supporting member arranged to be inserted in the tone arm of a phonograph, a horse-shoe magnet carried by said supporting member, a pair of U-shaped pole members secured to the opposite pole pieces of said horse-shoe magnet, said pole members having sets of pole faces directed toward each other, lugs extending from one end of said 45 pole members and extending parallel to each other, a screw device projecting through said lugs for predetermining the spacial relation of said pole members, means at opposite ends of said pole members for positively spacing 50 said pole faces, an electromagnetic winding positioned between said pole members and having a flat armature member extending through said electromagnetic winding and pivotally mounted with respect to said pole 55 faces, a stylus carrier connected to one end of said armature member, and a resilient member extending between the opposite end of said armature member and said horse-shoe magnet for normally biasing said armature 60 member in a central position and limiting the

movement of said armature member when mechanical vibrations are impressed upon said stylus carrier.

3. An electrical phonograph pick-up comprising a supporting member arranged for 70 insertion in the tone arm of a phonograph, a horse-shoe magnet carried by said supporting member, a pair of pole members having opposite pole faces directed toward each other, a lug projecting from the end of each pole member, a screw device passing through each lug and adjustable therein for selectively fixing the spacial relation of said pole faces, said pole members being positioned between the poles of said horse-shoe magnet, an electromagnetic winding positioned between said pole members, an armature member pivotally mounted between the pole faces at one end of said pole members and extending through 80 said electromagnetic winding and across the pole faces at the opposite ends of said pole members, a leaf spring member connected between said armature member and a fixed point for limiting the movement of one end of said armature member, and means for impressing mechanical vibrations upon the opposite end of said armature member for varying the magnetic condition of the electromagnetic winding.

4. An electrical phonograph pick-up comprising a supporting member arranged for 90 insertion in the tone arm of a phonograph, a horse-shoe magnet carried by said supporting member, a pair of pole members having opposite pole faces directed toward each other, said pole members being positioned between the poles of said horse-shoe magnet, an electromagnetic winding positioned between said pole members, an armature member pivotally mounted between the pole faces at one end of said pole members and extending through 100 said electromagnetic winding and across the pole faces at the opposite ends of said pole members, lugs protruding from said pole members, a screw device passing through said lugs and locked with respect to said lugs for selectively spacing the pole faces of said pole members, said armature member extending on opposite sides of said screw device and being flexibly connected to a portion of said horse-shoe magnet, a stylus carrier connected to the opposite end of said armature member whereby vibrations impressed upon a stylus inserted in said carrier may be transferred to said armature member 110 for variably controlling the magnetic condition of said electromagnetic winding.

5. An electrical phonograph pick-up device comprising a supporting member arranged to be inserted into the tone arm of a phonograph, a permanent magnet carried by said supporting member, said permanent magnet having parallel extending pole pieces, a pair of pole members each having aligned pole faces, said pole members being secured at 120

one end to the extremities of the pole pieces of said permanent magnet, lug members positioned on the opposite ends of said pole members, a screw threaded device for selectively spacing the pole faces of said pole members with respect to each other, an electromagnetic winding positioned within said pole members and having a hollow central core, a flat armature member pivotally mounted between opposed pole faces adjacent the extremities of the poles of said permanent magnet and extending through the hollow core of said electromagnetic winding and across the pole faces at the opposite ends of said pole members, a spring member extending between said magnet and one end of said armature for centering said armature between said pole faces, and a stylus carrier connected with the opposite end of said flat armature member whereby mechanical vibrations may be imparted to said flat armature member from a stylus within said carrier for varying the magnetic condition of said electromagnetic winding.

25 In testimony whereof I affix my signature.
MELVIN E. VANSICKLE.
